UNITED STATES PATENT OFFICE

JOHN E. MITCHELL, OF ST. LOUIS, MISSOURI

COTTON SEPARATING AND CLEANING MACHINE

Application filed January 21, 1927. Serial No. 162,597.

This invention relates to certain new and useful improvements in cotton extracting and cleaning machines, and has for its general object to provide a machine of this character which, in operation, will produce a higher degree of separation between the cotton and the hulls and trash mixed therewith than has been found possible with machines of this kind heretofore devised by me.

10 In earlier types of machines, such as that disclosed in my prior Patent No. 1,383,009, I have employed two saw cylinders with a hullboard co-operating with each saw cylinder, the second or lower cylinder being

15 used for recovering or reclaiming cotton from the hulls and trash discharged from the cylinder above. In this and all similar machines where a series of separations have been made by the action of saw cylinders carrying the cotton against rotating kicker or hulling rollers, the extra separations have always been made for the purpose of avoiding waste of cotton with the hulls and trash, rather than to effect a more complete separation of hulls and trash from the cotton. In other words, with the single separation brought about by the combination of the saw cylinder, kicker roll and hullboard, considerable cotton will escape with the hulls and

20 trash while, at the same time, considerable hulls and trash will pass through with the cotton.

It has, therefore, been necessary to make additional separations in an attempt to recover or reclaim cotton which would otherwise be wasted with the hulls and trash, and this has been done in the types of machines referred to; but it has now become necessary, by reason of the rougher cotton-harvesting methods now practiced, to subject the cotton, separated from the main body of hulls and trash, to one or more additional cleaning actions for the purpose of removing more of the trash and hulls.

45 It will be readily seen that in prior machines affording successive treatments, such as I have referred to, all of the hulls, trash and cotton escaping from the initial treatment must be dealt with in subsequent treatments, whereas, in my present invention, the

cotton is delivered from one separating unit to another and in each successive treatment, the hulls and trash separated from the cotton pass out of the machine.

According to the present invention, the elements of a saw cylinder, hullboard, kicker roll and doffer, characteristic of prior machines of my invention, are duplicated two or more times and are arranged in such relation to each other that the seed cotton in being doffed from the first saw cylinder is thrown onto another saw cylinder where the same cleaning operation is repeated, and from the second to the third cylinder, and so on, the operation being repeated as often as necessary to effect a thorough separation of all trash and hulls from the seed cotton.

In order that the purpose of this arrangement may be better understood, I would state that in the use of a single combination of the elements above referred to, a complete and thorough separation of the foreign matter from the seed cotton cannot be effected, for the reason that when the cotton is carried by the first saw cylinder under the first kicker roll, only a portion of each lock of cotton is brushed or scraped by the rotating kicker roll, and while that portion of each lock of cotton actually coming into contact with the kicker roll on the first saw cylinder may be thoroughly cleaned, any trash or hulls underneath the cotton engaged by the saw cylinder, where it does not come in contact with the kicker roll, is carried through by the saw cylinder to the doffer.

By duplicating or continuing the cleaning operations, obviously a very thorough and complete separation of hulls and trash from the seed cotton can be effected, due to the fact that the position of the locks of cotton will be continually changed so that hulls or trash which may not have been engaged by the kicker roll of the first saw cylinder will inevitably be engaged by the kicker roll of the second or successive saw cylinders.

The invention is illustrated in the accompanying drawings, which represents a cross-sectional view of my improved machine.

Referring to this drawing, the numeral 1 indicates a casing having an inlet spout 2 at

one end in which are located feed rollers 3. Beneath these feed rollers is mounted for rotation a breaker cylinder 4, the mixed cotton and hulls being delivered to the first saw cylinder 5 by the combined action of the feed rollers and breaker cylinder. Mounted above the saw cylinder 5 is a kicker roll 6 and located at a suitable point beyond the kicker roll is a doffing cylinder 7 for removing the cotton from the saw cylinder 5. Depending from the top of the casing beyond the doffing cylinder 7 is a partition 8, and slightly beyond this partition is mounted a second saw cylinder 9 with a co-operating kicker roll 10 and doffer cylinder 11. Beyond this kicker roll is a second partition 12, saw cylinder 13, kicker roll 14, and doffer cylinder 15. There may be as many cleaning units, comprising, essentially, a saw cylinder, kicker roll and doffer cylinder, as desired, but for convenience, I have restricted the illustration to an arrangement of three of such cleaning units. Beyond the last saw cylinder there is an opening 16 in the casing through which the cleaned cotton is discharged. Co-operating with the first saw cylinder 5 is a hull-board 17, the lower end of which defines a space 18 past the first saw cylinder for the escape of hulls. Beneath this saw cylinder there is a guard 19 terminating at one end in an inclined hull-board 20 co-operating with the second saw cylinder 9, its lower end defining a space 21 between it and the saw cylinder for the escape of hulls. In like manner, beneath the saw cylinder 9 there is a guard 22 which terminates at one end in a hullboard 23, the lower end of which defines a space 24 between the saw cylinder 13 and itself for the escape of hulls. Between the lower end of the hull-board 17 and the adjacent end of the guard 19, an opening 25 is provided for the escape of hulls out of the machine, and a corresponding opening 26 is provided in connection with the saw cylinder 9. Beneath the three saw cylinders, there is located a drag belt 27 comprising two chains mounted on sprocket wheels 28 and provided at intervals with cross bars 29 which extend the full width of the machine or length of the saw cylinders, so that all hulls and trash escaping through the openings 25, 26 and 24 fall through the bars to the bottom of the casing and are swept or dragged by the bars and discharged onto a screw-conveyor 30 which, in turn, discharges them from the machine through an outlet opening 31.

From the foregoing description, it will be apparent that as the seed cotton passes down the hullboard 17, the cotton will be engaged by the saw cylinder 5 and carried up beneath the kicker roll 6, which operates to knock back a large amount of the hulls and trash carried up with the cotton. These hulls and trash pass by the saw cylinder through the opening 18 and fall through the opening 25.

The cotton passing under the kicker roll 6 is removed from the saw cylinder 5 by the doffer 7 and thrown directly onto the second saw cylinder 9, and the preceding operation is repeated, the doffer 11 throwing the cotton from the saw cylinder 9 directly onto the saw cylinder 13, and the third doffer 15 discharging the thoroughly cleaned cotton through the opening 16.

It will be seen that the working surface of each saw cylinder after the first travels in an upward direction, that is, in a direction substantially opposed to that of the cotton thrown upon it by the doffer of the preceding saw cylinder. This arrangement permits the saw cylinders to raise the cotton while permitting the hulls to fall past the saw cylinder and out of the opening provided for the discharge of hulls near the bottom side of each saw cylinder.

While, as stated, additional saw cylinders with co-operating kicker rolls and doffers may be employed if the character and condition of the cotton, or the amount of trash to be removed, should make a larger number of treatments necessary, ordinarily the use of three cleaning units arranged as shown will effect a thorough separation of the cotton from the hulls and trash mixed therewith, so that for practical purposes, the cotton discharged from the last cleaning unit may be stated to be entirely free from hulls and trash.

It will be noted that the saw cylinders are arranged in horizontal order, which expedites doffing the cotton from one saw cylinder to another and at the same time providing separate and independent discharges for the trash and foreign matter removed.

This horizontal arrangement of the different groups of separating elements at once differentiates the machine from the vertical arrangement which is more desirable where the hulls and trash instead of the cotton is being subjected to a series of separations for the purpose of obtaining a greater yield or percentage of cotton.

It is not essential to the invention, however, that a strictly horizontal arrangement of the saw cylinders should be provided, as they could be arranged in a plane more or less inclined without departing from the spirit of the invention, the main essential being that the cotton separated by each saw cylinder shall be delivered to a succeeding saw cylinder and that the hulls and trash removed from the cotton in each treatment shall pass out of the machine and not be subjected to the action of a succeeding saw cylinder.

It will be apparent that the hulls passing through the first discharge outlet 18 will also have some cotton mixed with them, and in actual practice, it is contemplated to subject the discharge of the product past the first saw cylinder to a further cleaning action.

However, the present invention is not concerned with this feature and no illustration of the apparatus involved is deemed necessary.

I claim:

1. In a machine of the class described, a plurality of cotton separating and cleaning units arranged in operative relation to but independent of each other and in a substantially horizontal plane, each unit comprising a saw cylinder and a hullboard providing a space for the discharge of hulls and trash past the saw cylinder, and a doffer mounted in spaced relation to each saw cylinder and operating to remove from the saw cylinder the cotton separated thereby from the hulls and trash, together with such hulls and trash as may adhere to the separated cotton, and to deliver the same to the next saw cylinder in succession, each succeeding saw cylinder having its working surface moving in a direction opposed to that of the cotton thrown upon it by the doffer of the preceding saw cylinder.

25 2. In a machine of the class described, a plurality of cotton cleaning units arranged in operative relation to each other, each unit comprising a saw cylinder and a kicker roll co-operating therewith to separate some of
30 the hulls and trash from the cotton, and a doffer mounted in spaced relation to each saw cylinder and operating to remove the cotton from the saw cylinder after it has passed the kicker roll, and to deliver same, with the re-
35 maining hulls and trash, directly to the saw cylinder of the next succeeding cleaning unit, each succeeding saw cylinder having its working surface separated from the working surface of the preceding saw cylinder and
40 moving in a direction opposed to that of the cotton thrown upon it by the doffer of the preceding saw cylinder.

3. In a machine of the class described, a plurality of cotton cleaning units arranged in operative relation to each other in a substantially horizontal plane, each unit comprising a saw cylinder and a kicker roll cooperating therewith to separate some of the hulls and trash from the cotton, and a doffer 45 mounted in spaced relation to each saw cylinder and operating to remove the cotton from the saw cylinder after it has passed the kicker roll, and to deliver same, with the remaining hulls and trash, directly to the saw cylinder 50 50 of the next succeeding cleaning unit, each succeeding saw cylinder having its working surface separated from the working surface of the preceding saw cylinder and moving in a direction opposed to that of the cotton 55 60 thrown upon it by the doffer of the preceding saw cylinder.

4. In a machine of the class described, a plurality of cotton separating and cleaning units arranged in operative relation to but 65 independent of each other, each unit com-

prising a saw cylinder, a hullboard providing a space for the free discharge of hulls and trash past the saw cylinder, and a doffer mounted in spaced relation to the saw cylinder, each of said doffers being positioned and operating to deliver the separated cotton and such trash and hulls as may adhere thereto removed from its saw cylinder, directly to the saw cylinder of the next cleaning unit in succession.

5. In a machine of the class described, a plurality of cotton separating and cleaning units arranged in operative relation to but independent of each other and in a substantially horizontal plane, each unit comprising a saw cylinder, a hullboard providing a space for the free discharge of hulls and trash past the saw cylinder, and a doffer mounted in spaced relation to the saw cylinder and operating to remove from the saw-cylinder the cotton separated thereby from the hulls and trash, together with such hulls and trash as may adhere to the separated cotton, and to deliver the same directly to the next saw cylinder in succession.

In testimony whereof, I have hereunto set my hand.

JOHN E. MITCHELL.
